UNITED STATES PATENT OFFICE.

JOHN W. BROWN AND WILLIAM HESS, OF PHILADELPHIA, PENNSYLVANIA,
ASSIGNORS, BY DIRECT AND MESNE ASSIGNMENTS, TO BENJAMIN P. OB-
DYKE, INC., OF PHILADELPHIA, PENNSYLVANIA, A CORPORATION OF
DELAWARE.

SEAMING APPARATUS.

1,377,305.

Specification of Letters Patent. Patented May 10, 1921.

Application filed September 26, 1919. Serial No. 326,511.

To all whom it may concern:

Be it known that we, JOHN W. BROWN and WILLIAM HESS, citizens of the United States, residing at Philadelphia, in the county of Philadelphia and State of Pennsylvania, have invented certain new and useful Improvements in Seaming Apparatus; and we do hereby declare the following to be a full, clear, and exact description of the invention, such as will enable others skilled in the art to which it appertains to make and use the same.

This invention relates to improvements in seaming machines, and more particularly to such as are adapted for producing lock-joint seams in sheet metal.

The object in view is the reduction in the number and complexity of parts and increase in efficiency of machines of this type.

With this and further objects in view as will in part hereinafter become apparent and in part be stated, the invention comprises certain novel constructions, combinations and arrangements of parts as subsequently specified and claimed.

In the accompanying drawings—

Figure 1 is a view in side elevation of an apparatus embodying the features of the present invention, parts of the frame being broken away.

Fig. 2 is a horizontal section therethrough taken on the plane indicated by line 2—2 of Fig. 1.

Fig. 3 is a vertical section taken approximately on the planes indicated by line 3—3 of Fig. 1, parts being seen in elevation, and the parts being in the position assumed at the beginning of an operation.

Fig. 4 is a similar view of the same parts in the position assumed in the course of the tucking operation.

Fig. 5 is an enlarged, fragmentary elevation of the folder head and connected parts.

Fig. 6 is a transverse section taken on the plane indicated by line 6—6 of Fig. 5, the parts being in the initial position as seen in Fig. 5.

Fig. 7 is a similar section taken on the

plane indicated by line 7—7 of Fig. 5, the parts being in the course of the tucking operation as seen in Fig. 4.

Fig. 8 is a fragmentary, transverse section taken on the plane indicated by line 8—8 of Fig. 1, the parts being in the final position completing the cycle of operation just prior to return to the initial position.

Fig. 9 is a fragmentary, end view with the anvil plunger actuating elements shown in the position corresponding with that of the parts in Fig. 8.

Fig. 10 is a detail, end view of the right-hand tucker detached, one of the lifting rods therefor being seen in fragmentary side elevation.

Fig. 11 is a fragmentary section taken on the plane indicated by line 11—11 of Fig. 10.

Fig. 12 is an enlarged, detail, fragmentary section showing the parts in the second step of the operation or that immediately following the introduction of the sheets of metal which occurs while the parts are in the position seen in Fig. 3.

Fig. 13 is a similar view of the same parts in the position of the next step of the operation.

Fig. 14 is a similar view of the same parts in the position of the fifth step of the operation, the fourth step not being shown and consisting of the withdrawal of the folder head to the position seen in Fig. 14 before the advance of the tuckers.

Fig. 15 is a similar view of the same parts in the position of the seventh or final step of the operation, the sixth step not being illustrated and consisting of the withdrawal of the tuckers before the final descent of the folder head and the final blow of the hammer plunger.

Referring to the drawings by numerals, 1 indicates a bed or table sustained by legs 2, 2. Extending longitudinally of and through the table 1 is a slot 3 in which plays the anvil plunger or former 4, which consists of a flat plate arranged to move edgewise within slot 3 and having its lower edge resting upon a

longitudinally extending cam 5. The cam 5 is journaled in the end portions of the table 1 and to an extension of one of the journals is fixed a rocking lever 6 engaged near one 5 end by an operating spring 7 and near the other by an actuating link 8. The link 8 pivotally engages lever 6 and extends on an incline upwardly therefrom and is pivotally connected with an elbow or bell crank lever 9, which is pivoted at 10 to one of the 10 upstanding side frames 11 of the machine. The said side frames 11 are preferably connected across the top of the machine by a longitudinally arranged arched plate 12 for affording stability and rigidity of the parts. Journaled in the side frames 11 is a main drive shaft 13 to one end portion of which is fixed an actuating cam 14 whose cam surface engages a roller 15 journaled in the upper end 15 portion of lever 9, so that as the cam 14 revolves the lever 9 will at times permit the spring 7 to oscillate the cam shaft 5 in one direction so that the cam surface thereof acts to thrust the anvil plunger 4 upward 20 to the position seen in Figs. 12 and 13, where the plunger will rest and resist downward movement of itself not by virtue of the pressure of spring 7 but because the thrust on the plunger is delivered toward the axis of 25 the cam which remains stationary during such thrust and is sustained against lateral bodily movement both by its journals in the end portions of the table 1 and by appropriate intermediate supports 16, 16. The 30 cam 5 is given a contour for effecting the requisite thrust of plunger 4 and permitting its retraction, and the cam 14 is timed to permit the thrust by the action of spring 7 and to allow the retraction by the downward 35 movement of roller 15 and the resultant oscillation of cam shaft 5 in the opposite direction from the action of spring 7, whereby the cam assumes a position permitting the plunger 4 to descend by its own weight to 40 its lowermost position.

In line with and above the anvil plunger 4 is arranged the hammer plunger 17 which is carried by a folder head 18 resiliently sustained and stressed upwardly by vertical 45 supporting rods 19, 19 extending through eyes 20, 20 projecting laterally from head 18, the said rods 19 extending upward from said eyes and passing through lateral eyes 21, 21, outstanding from the plate 12. Nuts 50 or heads 22, 22 are arranged at or near the upper ends of rods 19, spaced above the eyes 21, and each rod is surrounded by a coiled spring 23 between the respective eye 21 and the head 22. Each of the rods 19 is also 55 formed with a corresponding head or nut 24 beneath the respective eye 20, so that the folder head 18 is resiliently sustained on the springs 23. Upstanding from the folder head 18 are brackets 25 in which are journaled rollers 26, each arranged to travel on

the edge of a cam 27, there being by preference at least two rollers 26 and a cam 27 for each roller. It will be obvious that a greater number of rollers and cams may be employed if desired, and in the instance of 70 a very short folder head a single cam 27 will be found adequate. The cams 27 are fixed to the drive shaft 13 and are of such peripheral contour as to effect the requisite 75 downward thrusts of the folder head 18 in timed relation to the other parts hereinafter stated.

The folder head 18 is formed with a longitudinally downwardly opening slot or deep groove 28 and from the lower edge of 80 the folder head 18 depends a pair of spaced folder lips 29, each consisting of a longitudinally arranged plate detachably fixed within and extending along the slot 28. The plates 29 may be fixed to the head 18 in 85 various ways, as by being bolted thereto by screws 30, or may be otherwise appropriately fixed to the head. The plates 29 are preferably beveled at their outer portions but their inner walls are straight and parallel and their upper edges form offsets or shoulders within the slot 28 and the hammer plunger 17 consists of a longitudinally-arranged plate snugly fitting and slidingly 90 mounted between the faces of the plates 29, the upper portion of the plunger being 95 formed into a T-head 31 overhanging the shoulders formed by the upper edges of plates 29 so that the plunger 17 is free to play up and down within the slot 28 for so 100 much thereof as is represented by the distance from the upper edges of plates 29 to the upper terminus of the slot. The head 18 is formed at spaced points with vertical bores or apertures 32, 32 in each of which 105 is arranged a spring 33 whose upper end portion is confined by a detachable cap 34 threaded into the upper end of the respective bore 32. The lower end of each spring 33 rests upon the T-head 31 of plunger 17 110 and each spring is tensioned to press the head constantly downward. It will thus be seen that the hammer plunger 17 is capable of being retracted when sufficient force is exerted on its lower end and the movement 115 of the plunger 17 upward may continue until the T-head 31 strikes the upper terminus of slot 28, but at times, as will hereinafter appear, it is desirable to lock plunger 17 against retraction to that extent and to hold 120 it against further retraction than is indicated in Fig. 7. To this end, laterally acting plungers 35, 35 are arranged to play into and out of the path of movement of the head 31 from opposite sides of the folder 125 head 18. To enable this action of the plungers 35, the head 18 is formed with lateral apertures 36 communicating with the upper portion of the slot 28, there being preferably three apertures 36 at one side of the 130

head 18 and two apertures at the other, the apertures 36 at one side being spaced equidistant apart along the head 18 and the apertures 36 at the other side being equally spaced between the transverse planes of the head 18 occupied by the first-mentioned three apertures 36. Obviously, any other number of apertures and coöperating parts may be utilized when preferred. A bracket 37 outstands from and is detachably fixed to the folder head 18 for each aperture 36 and extends across the aperture. Fixed to each plunger 35 and outstanding therefrom is a guiding and operating rod 38 which extends through an appropriate aperture in the respective bracket 37 and is guided thereby. Beyond the bracket 37 each rod 38 is surrounded by a spring 39 confined between the respective bracket 37 and a pin 40 at the outer end of the rod 38, so that the respective spring 39 is tensioned to press the rod 38 outward and thus tend constantly to withdraw the respective plunger 35 from within the path of travel of the head 31. By preference, the head 31 is slightly notched out at 41, and the head 18 is correspondingly notched out at 42 for each plunger 35 so that the plunger 35 in each instance may be slightly thicker than the distance represented by the space between the upper surface of the head 31 and the upper terminus of slot 28 when the head 31 is in contact with the plunger 35. The springs 39 retain plungers 35 in their outermost position, that is, the position indicated in Fig. 3, so that the hammer plunger 17 is not interrupted in its upward movement except when the plungers 35 are pressed inwardly by the contact of inwardly moving brackets 43, 43 carried by tuckers 44 hereinafter described.

During the course of operation, as will hereinafter be pointed out, the hammer plunger delivers to the seam being formed a finishing pressure or blow, and to this end the plunger 17 must be pressed downwardly with irresistible force so far as the material being operated upon is concerned. To effect this operation, the drive shaft 13 is provided with eccentrics and eccentric straps 45, 45, preferably three in number appropriately spaced apart along the shaft. Obviously a different number of eccentrics may be utilized. To each eccentric strap is connected a pitman or plunger rod 46, which projects downward through a bore or aperture 47 in the head 18, each rod 46 being guided by the walls of the aperture and the guide thus formed being elongated by the provision of sleeve-like bosses 48 surrounding the respective rods 46 and upstanding from the head 18. Each boss 48 is preferably formed integral with the head 18, but may be otherwise constructed when desired. Each rod 46 is of a length and each actuat-

ing eccentric therefor has a throw sufficient for causing the rod to press the hammer plunger 17 down to the position indicated in Fig. 15, this operation being timed by the location of the eccentrics to occur at the appropriate moment toward the conclusion of a cycle of operation as will be hereinafter stated.

The tuckers 44 are arranged at the opposite sides of the path of movement of anvil plunger 4, and each consists of a flat plate extending along the table 1 for a distance equal substantially to the length of the head 18, that edge of each plate nearer the plunger 4 being beveled at 49 to provide a rounded entering edge. Upstanding from each of the plates comprising the respective tuckers 44 are eyes 50 to which are pivoted links 51 extending outwardly to and pivotally connected with operating levers 52. Each of the links 51 is preferably provided with a turn-buckle intermediate its ends for facilitating adjustment for controlling the exact distance of shifting of the tuckers in their tucking operations. The number of links 51 and operating levers 52 may be varied as found desirable, but by preference in a machine of the size illustrated in the accompanying drawings there are two links and levers for each tucker 44, one pair of levers being arranged at one side of the machine and the other pair at the other side. The levers of one pair are fulcrumed on a shaft 53 and the other pair fulcrumed on a similar shaft 54, the shafts 53 and 54 extending for the length of the machine and being rigidly connected to the side frame 11. Each lever 52 extends upwardly above its respective fulcrum shaft and engages an operating cam carried and actuated by the drive shaft 13. These cams by preference consist of grooves or cam paths 55 formed in the faces of the cams 27, the cam path 55 in one face of one cam 27 being engaged by a lever 52 at one side of the machine and the cam path 55 in the opposite face of the same cam 27 being engaged by a lever 52 at the other side of the machine. Each lever 52, at its upper end, is provided with a lateral pin or laterally set roller 56 riding within and actuated by the respective cam path 55. Thus the tuckers 44 are adapted to be reciprocated across the table 1 toward and away from the path of movement of plunger 4 by the action of the levers 52, such reciprocal movement being timed and governed by the timing and contour of cam paths 55.

It will be noted that the pivoted link connections 51 leave the tuckers 44 free for such vertical play as may become desirable, and to facilitate the introduction of successive sheets of metal means are provided for lifting one of the tuckers 44 at the conclusion of a cycle of operation so as to provide

a free path of access for the sheet of metal to be introduced. To effect this lifting operation, one of the tuckers 44 is engaged by lifting rods 57, 57, one at each end of the tucker. Since the sheets of metal are to be fed in from the righthand side of the machine as seen in Figs. 3, 4 and 8, the particular tucker 44 engaged by rods 57 may be referred to as the righthand tucker. Each rod 57 is confined against edgewise movement by a guide consisting of a pair of laterally outstanding beads 58 fixed to and formed integral with the respective side frame 11. To the upper end of each rod 57 is pivotally connected a link 59 as best seen in Fig. 8, which in turn pivotally engages the outer end of an operating lever 60 fulcrumed at 61 on a pin outstanding from the respective side frame 11. The inner end of each lever 60 carries a roller 62 arranged to ride against a cam 63 fixed to and carried by the drive shaft 13. The cam 63 is timed to depress the inner end of levers 60 and thus elevate the righthand tucker 44 at the conclusion of each cycle of operation and to allow the said tucker to be lowered to rest upon the newly introduced sheet as the folding lips or folder head 18 descend to the position indicated in Fig. 13.

It is obvious, of course, that while each rod 57 must be so anchored to the tucker 44 as to cause the tucker to move up and down as described, the manner of anchorage must be such as to allow the tucker to be reciprocated by levers 52. To this end, the preferable form of anchorage of rods 58 is such as is illustrated in detail in Figs. 10 and 11, in which rod 57 is shown as provided with a foot 64 having a slot 65 through which projects an extension 66 from the tucker 44, the foot 64 being accommodated in a notched out portion or recess 65' in the end of the tucker. Thus the righthand tucker 44 may be reciprocated for a distance within the limits allowed by the excess length of slot 65 beyond the width of extension 66.

Power may be supplied from any source, not illustrated, as, for example, by a belt not shown engaging the fixed pulley 67 mounted on the drive shaft 13. The usual loose pulley 68 is also provided to receive the belt when the machine is temporarily thrown out of operation.

In operation, the parts being in the position indicated in Fig. 3, a sheet of metal is introduced across the table 1 beneath the righthand tucker 44, and the lefthand tucker 44 is tilted slightly by hand until the sheet is slid beneath it and lies with its edge portion, last introduced, across the slot 3. A second sheet is then passed beneath the righthand tucker 44 and placed with its first introduced edge portion overlying the edge portion of the former sheet. Thereupon the spring 7, released by the dropping of the roller 15 off

of the greater radius of cam 14 oscillates cam 5 and projects the anvil plunger 4 to its uppermost position as indicated in Fig. 12. Thus the lapped portions of the sheets are brought into contact with the hammer plunger 17 which presses down upon the sheets under spring pressure and while remaining thus in engagement with the sheets, the folding lips 29 descend to the position indicated in Fig. 13, the descent of the folder head 18 being accompanied by a corresponding descent of the righthand tucker 44. The sheets thus assume a flat position on the table 1 and the overlapping portions of the sheets are formed into a trough-like upstanding member of rectangular form in cross section. Cam 14 then depresses the roller 15 and thus oscillates cam 5 back to its initial position, and the anvil plunger 4 drops to the position indicated in Fig. 14, and at the same time the folder head 18 ascends under the action of springs 23, which action is limited by the contour of the edge portions of cams 27 so that the folder lips 29 only ascend to the position indicated in Fig. 14. Thus the just-formed trough-like overlapping portions of the sheets of metal are internally unsupported. Then the tuckers 44 approach each other until the tapered edges thereof engage the lower portions of the trough-like member and move said portions inward toward each other, sliding the sheets of metal across the table in this inward movement. At or just before the moment of contact of the tapered edges of tuckers 44 with the folded portions to be tucked, the upstanding brackets 43 will have come in contact with the stems 38 of plungers 35, and as the tuckers move inward the plungers 35 correspondingly move inward so as to interfere with and prevent any upward movement of the hammer plunger 17 beyond that seen in Fig. 14, so that the overlapping portions of the sheets of material being tucked may not bow upward or otherwise become distorted or out of the desired shape. The tuckers 44 continue their movement inward to and past the position seen in Fig. 14 until the adjacent edges of the tucked portions of the sheet are nearly in contact, the distance apart being taken up subsequently by the collapsing of the metal until the parts contact in the finished bead. Then the tuckers 44 are retracted to the position indicated in Fig. 15, it being observed that as they move outward the plungers 35 also move outward and leave the hammer plunger 17 for actuation by the rods 46. Thereupon the folder head 18 descends so that the lips 29 confine the tucked overlapped portions of the sheets and at the same time the hammer plunger 17 descends with its hammer blow under the action of the rods 46 until the parts assume the position shown in Fig. 15, whereat the seam is complete and so per-

fect as to be both oil and water tight. To avoid having the ridge or bead produced incident to the formation of the seam lie all at one face of the completed sheet, provision is made to have a portion of the thickness of such bead appear at the under face and the balance at the upper face, this being accomplished by the descent of the anvil plunger 4 beneath the plane of the upper surface of the table a distance equal to the distance to which the thickness of the bead beneath the finished sheet is to appear, while the hammer plunger 17 is proportioned to descend as much nearer to the plane of the table 1 as is represented by the descent of the bead into the slot 3.

Thereupon the folder head 18 ascends to the position seen in Fig. 3, and the parts are ready for another cycle of operation.

The invention herein disclosed appertains to the same type of machines covered by our co-pending applications, one filed July 10, 1918, Serial No. 244,202, and the other filed June 27, 1919, Serial No. 307,150, and this application may be considered a continuation of those applications in so far as the subject matter herein disclosed corresponds with that disclosed in said applications.

What is claimed is:

1. In seaming apparatus, the combination of a reciprocally-mounted anvil plunger, a folder having folding lips adapted to extend on opposite sides of the plunger and to fold sheets of material about the plunger to form an inverted, trough-shaped portion of the sheets, tuckers reciprocally mounted for approaching such trough-shaped portion laterally, a hammer plunger adapted to collapse the folds of the trough-shaped portion after the tucking operation thereon, and means for actuating all of said parts timed to cause the anvil plunger to retract after the formation of the trough-shaped portion, the folder to retract, the tuckers to advance and tuck parts of the trough-shaped portion under other parts thereof, tuckers to retract, the folder lips to descend and inclose the thus tucked trough-shaped portion and the hammer plunger to deliver a collapsing blow on such trough-shaped portion while thus confined.

2. In seaming apparatus, the combination of means for forming a trough-shaped portion of overlapping parts of sheets of material, means for tucking parts of the trough-shaped portion under other parts thereof, means for collapsing the parts of the trough-shaped portion to a tightly folded condition forming a bead, and means for supporting the sheets during such collapsing operation spaced between the levels of the collapsing means and that part of the trough-forming means against which the parts of the trough-shaped portion are collapsed, the parts being so proportioned with respect to each

other as to cause the bead thus formed to have its thickness divided and exposed partly at one face of the sheets operated upon and partly at the other.

3. In seaming apparatus, the combination with a slotted table adapted to support sheets of material to be operated upon with overlapping portions of the sheets lying across the slot, an anvil plunger reciprocally mounted in the slot, means for moving the plunger from a position below the plane of the surface of the table to a position with its upper portion above said plane, means for forming sheets over the portion of the anvil plunger above the table, means for tucking the thus formed portions of the sheets, and means for collapsing the folded and tucked portions of the sheets and for forcing the same into the slot into contact with the retracted anvil plunger.

4. In seaming apparatus, the combination with a table having a slot, of an anvil plunger reciprocally mounted in the slot, means for moving the plunger to a position with a portion of the plunger extending above the table, a reciprocally mounted folder head, said folder head being formed with a slot in line with the slot of the table, plates detachably connected to the folder head and forming folder lips spaced apart in position for folding sheets over the anvil plunger when the lips are moved past the projecting portion of the plunger, means independent of the anvil plunger for tucking portions of the folded parts of the sheets to underhanging positions, and means movable within the slot of the folder head for collapsing tucked portions of sheets.

5. In seaming apparatus, the combination with a table having a slot, of an anvil plunger reciprocally mounted in the slot, means for moving the plunger to a position with a portion of the plunger extending above the table, a reciprocally mounted folder head, said folder head being formed with a slot in line with the slot of the table, plates detachably connected to the folder head and forming folder lips spaced apart in position for folding sheets over the anvil plunger when the lips are moved past the projecting portion of the plunger, means for tucking a part of the folded portions of the sheets to an underhanging position, and means movable within the slot of the folder head for collapsing tucked portions of sheets, the detachable plates extending into the slot of the folder head in position for limiting the movement of said collapsing means.

6. In seaming apparatus, the combination with a table having a slot, of a reciprocally mounted anvil plunger therein adapted to be moved to a position with a portion of the plunger extending above the plane of the surface of the table, a folder head movable toward and away from the anvil plunger

- and having lips adapted to shape sheets over the anvil plunger, a hammer plunger reciprocally mounted between the lips and a spring pressing the hammer plunger toward 5 the anvil plunger.
7. In seaming apparatus, the combination with a table having a slot, of a reciprocally mounted anvil plunger therein adapted to be moved to a position with a portion of the 10 plunger extending above the plane of the surface of the table, a folder head movable toward and away from the anvil plunger and having lips adapted to shape sheets over the anvil plunger, a hammer plunger reciprocally mounted between the lips, and a 15 series of springs mounted in the folder head engaging the hammer plunger and stressing the same toward the anvil plunger.
8. In seaming apparatus, the combination 20 with a table having a slot, of a reciprocally mounted anvil plunger therein adapted to be moved to a position with a portion of the plunger extending above the plane of the surface of the table, a folder head movable toward and away from the anvil plunger and having lips adapted to shape sheets over the anvil plunger, a hammer plunger reciprocally mounted between the lips, a series of springs mounted in the 25 folder head engaging the hammer plunger and stressing the same toward the anvil plunger, and screw caps having threaded engagement with the folder head for retaining 30 springs in position.
35. 9. In seaming apparatus, the combination with a reciprocally mounted anvil plunger, a folder head having folding lips adapted to fold sheets of material about the plunger, means for operating the plunger and effecting withdrawal thereof after the formation of the sheets thereover, tucking means for pressing under portions of the formed sheets toward each other, a hammer plunger reciprocally mounted between the lips of the 40 folder head, and means controlled by the tuckers for positively limiting the movement of the hammer plunger in a direction away from the folded sheets during the 45 tucking operation.
50. 10. In seaming apparatus, the combination with a reciprocally mounted anvil plunger, a folder head having folding lips adapted to fold sheets of material about the plunger, means for operating the plunger and effecting withdrawal thereof after the formation of the sheets thereover, tucking means for pressing under portions of the formed sheets toward each other, a hammer plunger reciprocally mounted between the 55 lips of the folder head, a locking plunger mounted to reciprocate across the path and intercept the movement of the hammer plunger, a spring tensioned to withdraw the locking plunger from the path of the hammer plunger, and means carried by the tuckers 60

ing means for pressing the locking plunger against the tension of the spring into the path of the hammer plunger.

11. In seaming apparatus, the combination with a reciprocally mounted anvil plunger, 70 a folder head having folding lips adapted to fold sheets of material about the plunger, means for operating the plunger and effecting withdrawal thereof after the formation of the sheets thereover, laterally movable tuckers arranged at the opposite sides of the path of movement of the folder head, levers for reciprocating the tuckers, links pivoted to the tuckers and pivoted to the levers for transmitting movement from 75 the former to the latter, and means for collapsing formed and tucked portions of sheets.

12. In seaming apparatus, the combination with a reciprocally mounted anvil plunger, 80 a folder head having folding lips adapted to fold sheets of material about the plunger, means for operating the plunger and effecting withdrawal thereof after the formation of the sheets thereover, laterally movable tuckers arranged at the opposite sides of the path of movement of the folder head, levers for reciprocating the tuckers, 85 links pivoted to the tuckers and pivoted to the levers for transmitting movement from the former to the latter, and means for collapsing formed and tucked portions of sheets, each of the links being adjustable in 90 length.

13. In seaming apparatus, the combination with folding and collapsing means for 100 sheets of material, of a tucker reciprocally mounted for tucking a portion of a formed sheet prior to collapsing thereof, means for reciprocating said tucker toward and away 105 from the point of tucking, rods anchored to said tucker in position for leaving the same free for such reciprocating movement while engaging the tucker to cause it to move with the rods laterally of the path of reciprocation of the tucker, means for thus moving 110 the rods, and guides for the rods.

14. In seaming apparatus, the combination with a table, of reciprocally mounted 115 plungers arranged one at one side and the other at the other side of the face of the table, means for folding a sheet of material about one of the plungers when projecting beyond the face of the table toward the other plunger, reciprocating tuckers for 120 tucking portions of the folded parts of the sheet to underlying positions, and means for moving the plungers in timed relation for causing retraction of the first plunger and causing the other plunger to crush the folded and tucked sheet upon retraction of the 125 first plunger and tuckers.

15. In seaming apparatus, the combination with a table, of reciprocally mounted plungers arranged one at one side and the 130

- other at the other side of the face of the table, means for folding a sheet of material about one of the plungers when projecting beyond the face of the table toward the 5 other plunger, means for moving the plungers in timed relation for causing retraction of the first plunger and causing the other plunger to crush the folded sheet upon retraction of the first plunger, and means for 10 moving the sides of the folded portion of the sheet toward each other in timed relation to the operation of the plungers such as to effect said moving of the sides of the folded portion of the sheet between the retraction of the first plunger and the crushing 15 operation of the second.
16. In seaming apparatus, the combination with a table, of reciprocally mounted plungers alined and arranged one above and 20 one below the horizontal plane of the upper surface of the table, means for folding a sheet of material about the upper portion of the lower plunger when projected above the table, reciprocating tuckers for tucking 25 portions of the folded parts of the sheet to underlying positions, and means for moving the plungers and tuckers in timed relation for causing an upward projection of the lower plunger and a retraction thereof and 30 for causing the upper plunger to crush the folded and tucked sheet upon retraction of the lower plunger and the tuckers.
17. In seaming apparatus, the combination with a table, of reciprocally mounted 35 plungers alined and arranged one above and one below the horizontal plane of the upper surface of the table, means for folding a sheet of material about the upper portion of the lower plunger when at the extreme 40 of reciprocation in one direction, reciprocating tuckers for tucking portions of the folded parts of the sheet to underlying positions, and means for moving the plungers and tuckers in timed relation for causing the 45 upper plunger to crush the folded sheet upon retraction of the lower plunger and the tuckers.
18. In seaming apparatus, the combination of reciprocally mounted tuckers movable toward and away from each other, 50 means for forming a trough-like fold in a sheet of material with the fold projecting upward between the tuckers, the tuckers being located with respect to the fold forming 55 means as to cause the tucking edges of the tuckers when reciprocated to engage the fold along the lower edges or lines of junction thereof with the main portions of the sheet for moving such edges toward each 60 other and causing portions of the fold to underhang other portions thereof, and means for collapsing the fold subsequent to the action of the tuckers.
19. In seaming apparatus, the combination with a supporting table, of an anvil 65 plunger movable past the horizontal plane of the table, a hammer plunger in line with the anvil plunger and movable toward the same, a pair of folders arranged one at each side of the hammer plunger, a pair of 70 tuckers arranged laterally outside of the vertical planes of the folders, and means for actuating the anvil plunger, hammer plunger, folders and tuckers for causing the anvil plunger to move upward a sheet of material 75 lying on the table, followed by a downward movement of portions of the sheet under action of the folders converse to the movement of the anvil plunger for producing an inverted trough-shape of the sheet and a withdrawal of the anvil plunger and folders, 80 followed by an advance of the tuckers for causing the side walls of the trough of the sheet to be inclined, producing an undercut or overhang to the trough, and the withdrawal of the tuckers, followed by a movement of the hammer plunger toward the trough shape of the sheet for collapsing the same.
20. In seaming apparatus, the combination with a supporting table formed with a longitudinal slot, of an anvil plunger movable in the slot and means for reciprocating the same therein to and from a point above the level of the table and for sustaining the 90 anvil plunger elevated in timed relation to the movement of other parts, a reciprocating hammer plunger arranged above and in line with the anvil plunger, a reciprocally mounted folder at each side of the hammer 95 plunger, means for reciprocating the folders for moving the same downward past the plane of the upper end of the anvil plunger while the anvil plunger is sustained in its elevated position, whereby a sheet of material placed on the table across the anvil plunger will be first elevated by the anvil plunger and then have portions depressed by the folders for forming an inverted 100 trough, tuckers disposed at opposite sides of the resulting trough and each having an inclined surface presented toward the trough, and means for reciprocating the tuckers upon the withdrawal of the folders for pressing the lower edge portions of the 105 trough toward each other, and means for actuating the hammer plunger in timed relation to the movement of the tuckers for crushing down the trough upon the withdrawal of the tuckers.
21. In seaming apparatus, the combination with a table provided with a longitudinal slot, of a plunger reciprocating in the slot, means for reciprocating the plunger and for sustaining the plunger in an elevated position with its upper end above the plane of the table for elevating a sheet of material lying on the table, folders reciprocally mounted to move at opposite sides of the plunger, means for reciprocating the 115
- 120
- 125
- 130

folders for pressing portions of the sheets sustained by the plunger downward to form an inverted trough, and laterally-acting means for pressing the vertical walls of the inverted trough to inclined position upon withdrawal of the plunger.

22. In seaming apparatus, the combination with a table provided with a longitudinal slot, of a plunger reciprocating in the slot, means for reciprocating the plunger and for sustaining the plunger in an elevated position with its upper end above the plane of the table for elevating a sheet of material lying on the table, folders reciprocally mounted to move at opposite sides of the plunger, means for reciprocating the folders for pressing portions of the sheets sustained by the plunger downward to form an inverted trough, laterally-acting means for pressing the vertical walls of the inverted trough to inclined position upon withdrawal of the plunger, and means for collapsing and flattening the walls of the resulting trough.

23. In seaming apparatus, the combination with a table provided with a longitudinal slot, of an anvil plunger reciprocating in the slot, means for reciprocating the anvil plunger and for sustaining the same in an elevated position with its upper end above the plane of the table for elevating portions of a sheet of material lying on the table, folders reciprocally mounted to move at opposite sides of the plunger, means for reciprocating the folders for pressing portions of the sheet sustained by the plunger downward to form an inverted trough, laterally-acting means for pressing the vertical walls of the inverted trough to inclined position upon withdrawal of the anvil plunger, a hammer plunger disposed between the folders, and means for reciprocating the hammer plunger in timed relation to the movement of the anvil plunger for crushing the trough upon the withdrawal of the plunger.

24. In seaming apparatus, the combination of a table for supporting sheets of material to be joined, an anvil plunger movable relative to the table, folders movable in timed relation to the anvil plunger for folding sheets about the plunger, tuckers movable laterally with respect to the folded portions of sheets and in timed relation to the folder and anvil plunger, a hammer plunger movable in timed relation to the tuckers and anvil plunger, a single power shaft, operating means between the shaft and the anvil plunger, hammer plunger, folders and tuckers for operating the same in sequence to form a seam.

25. In seaming apparatus, the combination of a table for supporting sheets of material, a former arranged above the table, tuckers disposed at opposite sides of the former, a hammer plunger supported in the

former and movable relative thereto, and means for actuating said former, tuckers and hammer plunger in the sequence of the order named to form a seam.

26. In seaming apparatus, the combination of a table adapted to support sheets of material with overlapping edge portions, an anvil plunger reciprocally mounted and arranged to rise through the table beneath the overlapping portions of the sheets, a former above the table in alinement with the plunger, tuckers arranged laterally of the former, and a single operating means for actuating all of said parts to operate the same in sequence for forming a seam. 70

27. In seaming apparatus, the combination of means for forming a trough-like portion in material to be seamed, a spring-pressed hammer plunger for crushing the trough-like portion into a seam, a power shaft for actuating all of the operating means, an eccentric actuated by the power shaft, and a reciprocating shaft actuated by the eccentric in position for engaging and actuating the hammer plunger for causing it to deliver its crushing stroke. 80

28. In seaming apparatus, the combination with a table, of reciprocally mounted former plates movable relative to the table, means co-operating therewith for forming a trough-like portion in material to be seamed, an operating shaft, and means actuated thereby for operating said former plates and said co-operating means, a hammer plunger reciprocally mounted between said former plates and a reciprocally mounted rod actuated by said shaft and disposed for intermittently engaging and actuating said hammer plunger for moving the same to a position for crushing the trough-like portion. 95

29. In seaming apparatus, the combination with a table adapted to support sheets of material, means for forming a hollow trough-like fold in material on the table, tuckers movable laterally toward and away from the trough-like fold for shaping portions thereof to underhang other portions, one of said tuckers being movable toward and away from the table in addition to its movement toward and away from the fold, 110 and means for actuating the tuckers.

30. In seaming apparatus, the combination of a table adapted to support sheets of material, a cam arranged beneath the table, an anvil plunger resting on the cam and adapted to be shifted thereby to a position with a portion of the plunger extending above the table, a folder above the table movable relative to the anvil plunger for forming sheets of material over the projecting portion of the anvil plunger, a hammer plunger adapted to crush the thus-folded material when the anvil plunger is withdrawn, tuckers arranged to engage the thus-folded material for causing portions thereof to un- 120 130

derhang other portions prior to the crushing operation, a power shaft, a plurality of cams actuated thereby, and means actuated by the cams for operating the anvil plunger 5 actuating cam, the folders, the tuckers and the hammer plunger in timed relation for completing a seam.

In testimony whereof we affix our signatures in presence of two witnesses.
